COOLING APPARATUS

David W. R. Morgan, Swarthmore, Pa., assignor
to Westinghouse Electric & Manufacturing
Company, East Pittsburgh, Pa., a corporation
of Pennsylvania

Application October 20, 1933, Serial No. 694,510
Renewed February 7, 1935

22 Claims. (Cl. 62—152)

My invention relates to cooling apparatus of the type known as steam compressor or vapor jet refrigerating apparatus, and it has for an object to provide mechanism for controlling the operation thereof.

Steam jet refrigerating apparatus comprises an evaporating chamber into which liquid to be cooled is admitted, and one or more ejectors connected to the chamber for withdrawing vapor therefrom, thereby effecting a vacuum or reduced pressure in the chamber and consequent partial evaporation and cooling of the liquid therein. Inasmuch as an ejector is not well adapted for operation at partial load, a plurality of ejectors may be provided, which together provide the full refrigerating capacity, so that a smaller number of ejectors may be operated at partial load. A valve for each ejector may be provided, preferably between the evaporating chamber and the inlet of the ejector, which valve is closed when the ejector is shut down to prevent reverse flow of vapor therethrough to the evaporating chamber, which reverse flow of vapor would destroy the vacuum therein.

In accordance with my invention, I provide control mechanism which, in initiating operation of an ejector, first admits motive fluid to the ejector to establish the suction or ejecting action of the ejector, the vapor valve between the evaporating chamber and the ejector inlet being closed to prevent reverse flow of vapor into the evaporating chamber. After an interval of time sufficient to assure that the ejecting action of the ejector has been established, the vapor valve is opened, and the ejector is then effective to withdraw vapor from the evaporating chamber to effect refrigeration therein. In terminating operation of the ejector, the control mechanism effects closing of the vapor valve prior to or currently with shutting off of the motive fluid to the ejector, so that the passage through the ejector is open only when the ejecting action of the ejector is established, thereby preventing reverse flow of vapor therethrough into the evaporating chamber.

The above and other objects are effected by my invention as will be apparent from the following description and claims taken in connection with the accompanying drawings forming a part of this application, in which:

Fig. 1 is a diagrammatic view of steam jet refrigerating apparatus to which my novel control mechanism is applied;

Fig. 2 is a wiring diagram of the control sys-

tem used in connection with the apparatus shown in Fig. 1; and

Fig. 3 is a wiring diagram of a further feature which may be applied to the control system of Fig. 2.

Referring to the drawings more in detail, I show, in Fig. 1, an evaporating chamber 10 of any suitable construction, adapted to receive water or liquid or other combinations of liquid and solids to be cooled. A conduit 11 is connected to the bottom of the chamber 10 for conveying the cooled water to the point of use. Three ejectors, designated A, B and C, have their vapor or suction inlets connected to the chamber 10. They are connected at their discharge ends to a condenser 12 provided with an air ejector 13, condensate outlet 7, cooling water inlet 8 and cooling water outlet 9.

Each ejector includes a nozzle chamber 14 and a converging-diverging conduit portion 15. Steam for motivating each ejector is supplied to the nozzles in the nozzle chamber thereof through a branch conduit 16, a valve 17 being provided to control the flow of the motive fluid. The several branch conduits 16 are connected to a source 25 of steam through a main conduit 18. A vapor valve 19 is provided in the connection between the evaporator chamber 10 and the suction or vapor inlet of each ejector. A shut-off valve 21 is provided between the discharge end of each 30 ejector and the condenser 12.

The ejectors A, B and C together provide the full refrigerating capacity of the apparatus when operating at full load. For example, if the apparatus is designed for 300 tons capacity, each 35 ejector may be designed to provide 100 tons of refrigeration. Obviously, the refrigerating capacity may be divided among the ejectors in any desired proportions. The purpose of dividing the refrigerating capacity among a plurality of ejectors is to enable efficient operation at partial load by operating only a portion of the total number of ejectors. For example, 200 tons of refrigeration may be effected by operating 2 ejectors, which, operating at full capacity, provide maximum efficiency.

When the motive steam to one ejector is shut off, the steam jets which normally effect flow from the inlet to the outlet end of the ejector are discontinued, so that vapor may flow through 50 the ejector in the opposite direction, that is, from the condenser to the evaporating chamber, due to difference in pressure that exists between the evaporator and condenser. In order to prevent such reverse flow of vapor through any ejector 55

which is shut down, the vapor valve 19 is closed. The shut-off valves 21 are provided so that any one ejector may be isolated for repair by closing both its valves 19 and 21.

5 The control mechanism for operating the ejector valves includes reversible split-field motors 22^a, 22^b, and 22^c for operating the valves 17 of the ejectors A, B and C respectively, and similar reversible motors 23^a, 23^b, and 23^c for operating 10 the vapor valves 19 of the respective ejectors. The control mechanism further includes a thermostat 24 responsive to the temperature of the water cooled in the chamber 10. Referring to Fig. 2, this thermostat preferably includes a thermostatic bulb 25 placed in the conduit 11, an expansible bellows 26 and a tube 27 connecting the same to the bulb 25. The bellows 26 is arranged to operate switches 28^a, 28^b and 28^c which are adapted to control the ejectors A, B and C, respectively.

20 Each switch includes a contact 29 connected to one line conductor, L₁, and contacts 31 and 32 for initiating and terminating operation of the ejector, respectively. These switches may be of 25 the mercury type, in which the mercury is adapted to connect the contacts 29 and 31 when tilted to the left for initiating operation of the control ejector, and to connect contacts 29 and 32 when tilted to the right for terminating action 30 of the control ejector. The three switches 28^a, 28^b, and 28^c are arranged at varying angles so as to successively close the contacts for initiating 35 operation of the respective ejectors upon expansion of the bellows 26 in response to successive increases in temperature of the water being cooled, and to close the contacts for successively terminating operation of the several ejectors upon contraction of the bellows 26 in response to successive decreases in temperature of the 40 water being cooled.

45 I preferably provide a drum controller for effecting operation of the valves 17 and 19 in the desired sequence and also for effecting the desired time delay between operation of the valves. Preferably, an individual drum controller is provided for each ejector, the ejectors A, B and C being provided with drum controllers 33^a, 33^b and 33^c, respectively. Each drum controller includes a drum 30 driven by a motor 34 through 50 reduction gearing 35. The drum 30 is illustrated in conventional developed view.

55 The drum controller 33^a for the ejector A includes contact fingers 37, 38 and 39 and a segment 41 for controlling operation of the drum controller. The contact fingers 37 and 38 are connected to the contacts 31 and 32, respectively, of the thermostatic switch 28^a. The contact finger 39 is connected to one terminal of the motor 34, the other terminal thereof being 60 connected to the line conductor L₂. The segment 41 is formed to connect the contact fingers 37 and 39 while the drum moves from "off" to "on" position, and to connect the contact fingers 38 and 39 from "on" to "off" position. The drum controller further includes a contact finger 42 connected to the line conductor L₁, and contact fingers 43 and 44 connected to the valve opening field windings of the valve operating motors 22^a and 23^a, respectively, and contacts 45 and 46 connected to the valve closing field windings of said 65 respective motors. A segment 47, located between the "off" and "on" positions of the drum, is formed as shown on the drawings to connect the contact fingers 42 and 43 immediately after 70 the drum leaves the "off" position, and to con-

nect the contact fingers 42 and 44 at the end of a predetermined interval of time thereafter. This predetermined interval of time is measured by the time required for movement of the drum, which moves at a constant rate of speed, between 5 the positions at which the segment 47 engages the contact fingers 43 and 44. A third contact segment 48 is located between the "on" and "off" positions of the drum, formed as shown on the drawings to connect the contact fingers 42 and 46 immediately after the drum leaves the "on" position, and to connect the contact fingers 42 and 45 at the end of a predetermined interval 10 of time thereafter.

15 The drum controller 33^b for operating the valves 22^b and 23^b of the ejector B and the drum controller 33^c for operating the valves 22^c and 23^c of the ejector C are identical with the drum controller 33^a described above.

20 The remaining terminal of each valve operating motor is connected, as shown on the drawings, to the line conductor L₂. Each of the field windings is provided with a limit switch 49 for terminating operation of the motor upon completion of the valve movement. Cut-out switches 25 51, 52 and 53 are provided in the conductors between the contacts 31 and 47 of the respective ejectors. Each switch is operated by the shut-off valve 21 of the ejector, being opened whenever the shut-off valve is closed. In this manner, whenever the valve 21 is closed for isolating an ejector, the control mechanism for initiating operation of that ejector is rendered inoperative.

30 The operation of the above described apparatus is as follows: In the position shown on the drawings, the thermostat 24 is subjected to a temperature below the temperature at which the first ejector is placed in operation, and all of the ejectors are shut down. Assume now that, due to refrigerating load, the temperature increases 35 sufficiently to call for operation of one ejector. The expansion of the bellows 26 tilts the thermostatic switches to the left, the switch 28^a being tilted sufficiently that the mercury therein flows to the left and connects the contacts 29 and 31. 40 The circuit is now completed for effecting operation of the drum controller 33^a from the "off" to the "on" position, the circuit extending from line conductor L₁, through contacts 29 and 31 of the thermostatic switch, through the cut-out switch 51, contacts 37 and 39 and segment 41, and motor 34 to the line conductor L₂. The movement of the drum 30, as seen on the drawings, is upwardly. Immediately after movement 45 of the drum has begun, the bridging of the contacts 42 and 43 closes the circuit to the valve opening field winding and the armature of the steam valve motor 22^a, which opens the steam valve 17 for supplying steam to the nozzles of the ejector A. This circuit is traced as follows: 50 From the line conductor L₁ through the contacts 42 and 43 and the segment 47, and the valve opening field winding and armature of the motor 22^a to the line conductor L₂.

55 The drum 30 continues to rotate at a constant rate of speed, and at the end of a predetermined period of time, during which the ejecting action or suction of the ejector A is established, the segment 47 engages the contact member 44. A circuit through the valve opening field winding 60 and armature of the vapor valve motor 23^a is thus completed, the motor then operating to open the valve 19. At the end of a further period of time which is sufficient to permit opening of the valve 19 to be completed, the segment 41 disen- 65

gages the contact finger 37, terminating further movement of the drum controller. At the same time, the segment 41 engages the contact 38, thereby placing the drum controller in condition 5 to be operated from "on" to "off" position when the thermostatic switch 28^a is tilted in the opposite direction to bridge the contacts 29 and 32. The ejector A now operates to withdraw vapor from the evaporating chamber 10 and to dis- 10 charge the same into the condenser 12, thereby cooling the remaining water in the chamber 10, in the usual manner of steam jet refrigerating apparatus.

The apparatus is now operating to provide 100 15 tons of refrigeration for cooling. If a greater amount of cooling is required, the temperature of the water will again increase to a higher temperature, in response to which the thermostat 24 will tilt the thermostatic switch 28^b to the left and 20 initiate operation of the ejector B in the same manner set forth above. Likewise, a still further increase in temperature will result in the thermostatic switch 28^c effecting operation of the ejector C. 25 When the refrigerating load again decreases, the thermostatic switches 28^c, 28^b, and 28^a operate in response to successively lower predetermined minimum temperatures to terminate operation of the ejectors C, B, and A. Operation of 30 each ejector is terminated in the following manner:

Assume that the ejector A is in operation and that the temperature of the water decreases below a predetermined minimum temperature, indicating that further cooling action is not presently required. The thermostat 24 then tilts the switch 28^a to the right, causing the mercury to bridge the contacts 29 and 32. A circuit to the motor 34 is then completed, extending from line 40 conductor L₁ through contacts 29 and 32 of the switch 28^a, contact 38, segment 41, contact 39, and motor 34 to line conductor L₂. The drum 30 now moves from its "on" position to the "off" position. Immediately after leaving the "on" 45 position, the segment 48 bridges the contacts 42 and 46, thereby completing a circuit to the valve closing field winding of the vapor valve motor 23^a, effecting operation of the motor to close the valve 19. At the end of a predetermined interval 50 of time thereafter, sufficient to assure complete closing of the valve 19, the segment 48 connects the contact fingers 42 and 45, completing a circuit to the valve closing field winding of the steam valve motor 22^a, whereupon the motor 22^a 55 operates to close the steam valve 17 of the ejector A. Closing movement of the valves 19 and 17 is completed by the time that the drum 30 reaches the "off" position, at which the segment 41 disengages the contact 38 to discontinue movement 60 of the drum and engaging the contact 37 to render the drum controller operable for again initiating operation of the ejector.

If it is desired to isolate one of the ejectors for service or repair, the valve 21 of that ejector is 65 closed. For example, assume that it is desired to isolate the ejector B. Closing the valve 21 of that ejector automatically opens the cut-off switch 52, thereby rendering the drum controller 33 for that ejector inoperable. In this case, if 70 the temperature of the water discharged through the conduit 11 rises to call for operation of a second ejector, the thermostat 24 will tilt the switch 28^b to connect the contacts 29 and 31. Upon failure of the ejector B to start, the con- 75 tinued refrigeration load not provided for will

effect further increase in temperature, in response to which the thermostat 24 will tilt the switch 28^c to initiate operation of the ejector C. In this way, isolation of one ejector will automatically cause the next ejector in series to be 5 operated to supply the required refrigeration load, although, in this case, a slightly higher temperature will be obtained.

In Fig. 3, I show a modified switch arrangement which may be used in place of the cut-out switches 51, 52 and 53, whereby, when any one ejector is isolated, the operation of the succeeding ejectors is advanced one step. The relation of Fig. 3 to the remainder of the control mechanism may be readily seen by placing Fig. 3 over 15 the thermostatic and cut-out switches of Fig. 2. The switches 51', 52', and 53' are operated by the valves 21 of the ejectors A, B, and C, respectively, each being moved to its upper position when the valve is opened and downwardly when the valve 20 is closed. The switch 51' includes contacts 54 and 55 adapted to connect the contacts 31 and 32 of the thermostatic switch 28^a to the contact fingers 37 and 38 of the controller 33^a in their upper position and to conductors 56 and 57 in 25 their lower position. It further includes similar movable contacts 58 and 59 adapted to connect the contacts of the switch 28^b to the conductors 56 and 57 in their upper position and to conductors 61 and 62 in their lower position. It also 30 includes contacts 63 and 64 adapted to connect the switch 28^c to the conductors 61 and 62 in the upper position.

The switch 52' includes contacts 65 and 66 adapted to connect the conductors 56 and 57 35 to the controller 35^b in the upper position and to the controller 33^c in their lower position. It further includes contacts 67 and 68 adapted to connect the conductors 61 and 62 to the controller 33^c in their upper position. The switch 40 53' merely open-circuits the conductor connected to the contact 37 of the controller 33^c to prevent operation of the ejector C from being initiated, there being no further ejectors to be operated when ejector C is isolated. 45

The operation of the arrangement shown in Fig. 3 is as follows: When all of the ejectors are in operation and the valves 21 are opened, the switches 51', 52', and 53' are in their upper positions. The thermostat 28^a controls the ejector 50 A, since the contacts 54 and 55 connect the switch 28^a to the controller 33^a. The switch 28^b controls the ejector B, the contacts 58 and 59 connecting the switch to the conductors 56 and 57 which are, in turn, connected through the contacts 65 and 66 to the controller 33^b. The switch 28^c controls the ejector C, since the movable contacts 63 and 64 connect the switch to the conductors 61 and 62, which are in turn connected through the movable contacts 67 and 68 to the controller 33^c, the switch 53' being closed to permit operation of the ejector C. 55 60

If, now, the ejector A is isolated, the movable contacts of the switch 51' are moved to their lower positions. The operation of the ejectors B and 65 C is now advanced one step, these ejectors responding to switches 28^a and 28^b, respectively, instead of switches 28^b and 28^c, respectively. This is due to the fact that the movable contacts 54 and 55 connected to the switch 28^a now engage 70 the conductors 56 and 57, which connect with the controller 33^b through the movable contacts 65 and 66, and to the fact that the movable contacts 58 and 59 connect the switch 28^b to the conductors 61 and 62 which control the controller 33^c. 75

through the movable contacts 67 and 68. Assume now that the ejector B is also isolated by closing its valve 21, causing the switch 52' to be moved downwardly. In this case, the switch 28^a controls 5 the ejector C, being connected to the controller 33^c through the movable contacts 54 and 55, the conductors 56 and 57, and the movable contacts 65 and 66.

Assume that the ejectors A and C are operable 10 but that the ejector B is isolated, the switch 52' being in its lower position. In this case, the switch 28^a controls the ejector A, but the switch 28^b controls the ejector C, the thermostat 28^b being connected through the movable contacts 58 15 and 59, the conductors 56 and 57, and the movable contacts 65 and 66 to the controller 33^c. When the ejector C is isolated, the switch 53' merely prevents operation of the ejector C, there being no further ejectors to be placed in operation.

20 In the arrangement shown in Fig. 3, it will be noted that, when any one ejector is isolated, the operation of all the succeeding ejectors in operation is advanced one step, while any preceding ejector not isolated is not affected thereby. With 25 this arrangement, when the refrigerating load requires operation of say two ejectors, operation of that number of ejectors, if available, is effected without waiting for a higher temperature than is otherwise required to effect operation of the first 30 two ejectors.

From the above description, it will be seen that I have provided control mechanism whereby operation of one or more ejectors may be controlled in such a way that reverse flow through any 35 ejectors not in operation is prevented. This is effected by closing the vapor valve, that is, the valve between the evaporating chamber and the ejector, at all times that the ejecting action or suction of the jets in the ejector is not established.

40 While I have shown my invention in but one form, it will be obvious to those skilled in the art that it is not so obvious but is susceptible of various changes and modifications, without departing 45 from the spirit thereof, and I desire, therefore, that only such limitations shall be placed thereupon as are imposed by the prior art or as are specifically set forth in the appended claims.

What I claim is:

50 1. In cooling apparatus, the combination of an evaporating chamber adapted to receive liquid to be partially evaporated and cooled, fluid translating means for withdrawing vapor from said chamber, means for controlling the admission of motive fluid to said translating means, means for controlling the flow of vapor from the chamber to the fluid translating means, and means for operating the motive fluid controlling means first and the vapor flow controlling means last when initiating operation of the fluid translating means and the vapor flow controlling means first and the motive fluid controlling means last when terminating operation of the fluid translating means.

65 2. In cooling apparatus, the combination of an evaporating chamber adapted to receive liquid to be partially evaporated and cooled, fluid translating means for withdrawing vapor from said chamber, means for controlling the admission of motive fluid to said translating means, means for controlling the flow of vapor from the chamber to the fluid translating means, and means responsive to a condition of the cooled liquid for operating the motive fluid controlling means first and the vapor flow controlling means last when initiating operation of the fluid translating means,

said condition responsive means being effective to operate the motive fluid controlling means and the vapor flow controlling means, the latter at least as early as the former, when terminating operation of the fluid translating means. 5

3. In cooling apparatus, the combination of an evaporating chamber adapted to receive liquid to be partially evaporated and cooled, fluid translating means for withdrawing vapor from said chamber, means for controlling the admission of motive fluid to said translating means, means for controlling the flow of vapor from the chamber to the fluid translating means, and means responsive to a condition of the cooled liquid for operating the motive fluid controlling means first and the vapor flow controlling means last when initiating operation of the fluid translating means and the vapor flow controlling means first and the motive fluid controlling means last when terminating operation of the fluid translating means. 10

4. In cooling apparatus, the combination of an evaporating chamber adapted to receive liquid to be partially evaporated and cooled, an ejector for withdrawing vapor from said chamber, means for controlling the admission of motive fluid to said ejector, means for controlling the flow of vapor from the chamber to the ejector, and means for operating the motive fluid controlling means first and the vapor flow controlling means last when initiating operation of the ejector and the vapor flow controlling means and the motive fluid controlling means, the former at least as early as the latter, when terminating operation of the ejector. 15

5. In cooling apparatus, the combination of an evaporating chamber adapted to receive liquid to be partially evaporated and cooled, an ejector for withdrawing vapor from the chamber, means for controlling the admission of motive fluid to the ejector, means for controlling the flow of vapor from the chamber to the ejector, and means for automatically operating the motive fluid controlling means first and the flow controlling means second when initiating operation of the ejector and the flow controlling means first and the motive fluid controlling means second when terminating operation of the ejector. 20

6. In cooling apparatus, the combination of an evaporating chamber adapted to receive liquid to be partially evaporated and cooled, an ejector for withdrawing vapor from the chamber, means for controlling the admission of motive fluid to the ejector, means for controlling the flow of vapor from the chamber to the ejector, means responsive to a condition of the cooled liquid for operating the motive fluid controlling means first and the vapor flow controlling means second when initiating operation of the ejector and the flow controlling means and the motive fluid controlling means, the former at least as early as the latter, when terminating operation of the ejector. 25

7. In cooling apparatus, the combination of an evaporating chamber adapted to receive liquid to be partially evaporated and cooled, an ejector for withdrawing vapor from the chamber, means for controlling the admission of motive fluid to the ejector, means for controlling the flow of vapor from the chamber to the ejector, and means responsive to a condition of the cooled liquid for operating the motive fluid controlling means first and the vapor flow controlling means second when initiating operation of the ejector and the flow controlling means first and the motive fluid controlling means second when terminating operation of the ejector. 30

8. In cooling apparatus, the combination of an 35

5 evaporator chamber adapted to receive liquid to be partially evaporated and cooled, an ejector for withdrawing vapor from the chamber, a valve for controlling the admission of motive fluid to the 5 ejector, a valve for controlling the flow of vapor between the chamber and the ejector, and means responsive to a predetermined maximum temperature of the cooled liquid for opening said valves and including time delay means for delaying 10 opening of the vapor valve for a predetermined period of time after opening of the motive fluid valve and responsive to a predetermined minimum temperature for closing said valves.

9. In cooling apparatus, the combination of an 15 evaporator chamber adapted to receive liquid to be partially evaporated and cooled, an ejector for withdrawing vapor from the chamber, a valve for controlling the admission of motive fluid to the 20 ejector, a valve for controlling the flow of vapor between the chamber and the ejector, and means 25 responsive to a predetermined maximum temperature of the cooled liquid for opening said valves and including time delay means for delaying opening of the vapor valve for a predetermined period of time after opening of the motive 30 fluid valve, and responsive to a predetermined minimum temperature for closing said valves and including time delay means for delaying closing of the motive fluid valve for a predetermined period of time after closing the vapor valve.

10. In cooling apparatus, the combination of an evaporating chamber adapted to receive liquid to be partially evaporated and cooled, a plurality of 35 ejectors for withdrawing vapor from said chamber, a condenser for condensing vapor discharged by said ejectors, at least one of said ejectors having a pair of valves associated therewith and including one valve for controlling the admission of motive fluid to the ejector, and a second valve for 40 controlling the flow of vapor from the chamber to the ejector, and means for opening the first and second-mentioned valves sequentially in the order named when initiating operation of the ejector, and for closing said first and second-mentioned 45 valves sequentially in the reverse order when terminating operation of the ejector.

11. In cooling apparatus, the combination of an evaporating chamber adapted to receive liquid to be partially evaporated and cooled, a plurality of 50 ejectors for withdrawing vapor from said chamber, a condenser for condensing vapor discharged by said ejectors, a plurality of valves associated with each of said ejectors and including one valve for controlling the admission of motive fluid to each ejector and a second valve for 55 controlling the flow of vapor from said chamber to each ejector, and means for controlling the operation of the ejectors and including means for opening the first-mentioned valve of each ejector before opening the second-mentioned valve thereof when initiating operation of the ejector, and closing the second-mentioned valve of the ejector before closing the first-mentioned valve thereof when terminating operation of the ejector.

60 12. In cooling apparatus, the combination of an evaporating chamber adapted to receive liquid to be partially evaporated and cooled, a plurality of 65 ejectors for withdrawing vapor from said chamber, a condenser for condensing vapor discharged by said ejectors, a plurality of valves associated with each of said ejectors and including one valve for controlling the admission of motive fluid to each ejector and a second valve for 70 controlling the flow of vapor from said chamber to each ejector, and means responsive to a condition

of the cooled liquid for controlling the operation of the ejectors and including means for opening the first-mentioned valve of each ejector before opening the second-mentioned valve thereof when initiating operation of the ejector, and closing the second-mentioned valve of the ejector before closing the first-mentioned valve thereof when terminating operation of the ejector. 5

13. In cooling apparatus, the combination of an evaporating chamber adapted to receive liquid to be partially evaporated and cooled, a plurality of ejectors for withdrawing vapor from said chamber, a condenser for condensing vapor discharged by said ejectors, a plurality of valves associated with each of said ejectors and including one valve for controlling the admission of motive fluid to the ejector and a second valve for controlling the flow of vapor from said chamber to the ejector, and means for initiating and terminating operation of the ejectors in sequence, 20 and including means for opening the first mentioned valve of each ejector before opening the second mentioned valve thereof when initiating operation of the ejector, and closing the second mentioned valve of the ejector before closing the first mentioned valve thereof when terminating operation of the ejector. 15

14. In cooling apparatus, the combination of an evaporating chamber adapted to receive liquid to be partially evaporated and cooled, a plurality of ejectors for withdrawing vapor from said chamber, a condenser for condensing vapor discharged by said ejectors, a plurality of valves movable to closed positions for respectively isolating the ejectors from the condenser, means responsive to the temperature of the cooled water for automatically initiating and terminating operation of the ejectors in sequence, and means operated by the valves when closed for discontinuing the control of their respective ejectors by 30 said temperature responsive means. 35

15. In cooling apparatus, the combination of an evaporating chamber adapted to receive liquid to be partially evaporated and cooled, a plurality of ejectors for withdrawing vapor from said chamber, a condenser for condensing vapor discharged by said ejectors, a plurality of valves movable to closed positions for respectively isolating the ejectors from the condenser, means responsive to the temperature of the cooled water for initiating and terminating operation of the 40 ejectors step by step, and means for advancing by one step the operation of succeeding ejectors when a preceding ejector is isolated from the condenser by the closing of its associated valve. 45

16. In cooling apparatus, the combination of an evaporating chamber adapted to receive liquid to be partially evaporated and cooled, a plurality of ejectors arranged in parallel for withdrawing vapor from the chamber, a condenser for condensing vapor discharged by said ejectors, a plurality of valves associated with each ejector including a valve for controlling the flow of motive fluid to the ejector, a second valve for controlling the flow of vapor from the chamber to the ejector and a third valve for isolating the ejector from the condenser, means responsive to the temperature of the cooled liquid for initiating and terminating operation of the ejectors, step by step, and including means for sequentially opening the first and second-mentioned valves in the order named when initiating the operation of an ejector and for closing said first and second valves in a reverse order when terminating operation of an ejector and means for advancing by one step. 55 60 65 70 75

the operation of succeeding ejectors when a preceding ejector is isolated from the condenser by the closing of its associated valve.

17. Apparatus for supplying a refrigerating demand comprising evaporator means adapted to contain liquid to be evaporated, a plurality of ejectors for withdrawing vapor from said means to effect cooling by evaporation of liquid therein, and means for automatically effecting successive increases in total ejector capacity in operation in response to successively higher temperatures of liquid in said evaporator means, respectively.

18. In cooling apparatus, the combination of evaporator means, a plurality of compressor elements for removing vapor from said evaporator means to effect cooling by evaporation of liquid therein, said evaporator means and said compressors supplying a common cooling demand, a thermostatic element responsive to a temperature maintained at a low value by the cooling apparatus, and means controlled by said thermostatic element and operating automatically to initiate operation of said compressors successively as said temperature attains successively higher values.

19. In cooling apparatus, the combination of evaporator means, a plurality of compressor elements for removing vapor from said evaporator means to effect cooling by evaporation of liquid therein, said evaporator means and said compressor elements supplying a common cooling demand, and means for controlling said compressor elements including a thermostatic element responsive to a temperature maintained at a low value by the cooling apparatus, and a plurality of electric switches actuated by said thermostatic element for controlling said compressor elements, respectively, said switches being arranged to be closed in sequence by said thermostatic element as the latter responds to successively higher values of said temperature.

20. Cooling apparatus for supplying a refrigerating demand comprising evaporator means adapted to contain liquid to be evaporated, a plurality of ejectors for withdrawing vapor from

said evaporator means to effect cooling by evaporation of liquid therein, and means for controlling said ejectors including a thermostatic element responsive to the temperature of cooled liquid in said evaporator means and means controlled by said thermostatic element for increasing the number of ejectors in operation as said thermostatic element responds to increase in said temperature and vice versa.

21. Cooling apparatus for supplying a refrigerating demand comprising evaporator means adapted to contain liquid to be evaporated, a plurality of ejectors for withdrawing vapor from said evaporator means to effect cooling by evaporation of liquid therein, and means for controlling said ejectors including a thermostatic element responsive to the temperature of cooled liquid in said evaporator means and a plurality of electric switches actuated by said thermostatic element for controlling said ejectors, respectively, said switches being arranged to be closed in sequence by said thermostatic element as the latter responds to successively higher values of said temperature.

22. In cooling apparatus of the vapor jet type, the combination of an evaporator chamber, means for delivering liquid to be cooled to said chamber, means for removing cooled liquid from said chamber, a plurality of ejectors for removing vapor from said chamber to effect cooling of the liquid therein by partial evaporation thereof, one of said ejectors having a motive fluid admission valve and a vapor valve controlling flow of vapor from said chamber to said ejector, and means for controlling said valves of said one ejector in response to a load condition of the apparatus, said last-named means being operable, upon initiating operation of the ejector, to open said vapor valve only when said admission valve is open and the ejecting action of the ejector is established, and being operable, upon terminating operation of the ejector, to close said admission valve only when the vapor valve is closed.
